UNITED STATES PATENT OFFICE.

ADOLF A. MEYER, OF NEW YORK, N. Y.

PATTERN AND METHOD OF MAKING THE SAME.

Application filed May 24, 1922. Serial No. 563,403.

To all whom it may concern:

Be it known that I, ADOLF A. MEYER, a citizen of the United States, and a resident of the city of New York, borough of Manhattan, in the county and State of New York, have invented a new and Improved Pattern and Method of Making the Same, of which the following is a full, clear, and exact description.

10 This invention relates to a pattern and method of making the same, and has for an object the provision of a simple pattern and method of making the same whereby a person preparing a pattern and draping a model 15 with the pattern of a garment to be made of such material as fur can readily and much more effectively visualize the harmony and arrangement of the various parts of the garment as the pattern prepared in accordance 20 with my method is draped on a model.

Another object resides in the particular construction and arrangement of parts which are hereinafter described and claimed and shown in the accompanying drawings.

25 The invention is schematically illustrated in the drawings, of which

Figure 1 is a view of one form of pattern.

Figure 2 is a view of a model draped with a pattern which has been prepared to simulate as closely as possible the harmony, color and arrangement of the finished garment.

30 In the garment industry, and especially in making garments of costly material such as fur, it is impossible for the artist to easily 35 visualize on a model which has been draped with the ordinary pattern, the effect of the finished garment. On the other hand, it is impossible to cut up costly material until it is absolutely determined just how it should 40 be cut, without wasting considerable material. To avoid this waste, I have evolved my pattern and method of making the same whereby the artist can know substantially accurately in advance just what cutting to 45 make.

In order to bring about this result, I take any material suitable to form a pattern, such as paper, cloth, or any other desired substance, and treat it in any manner, such as 50 by any well known printing process, so that one or both of its surfaces is prepared with the appearance of the material of which the finished garment is made. For instance, if the garment is made of a particular kind 55 of fur, I take my pattern material and have it treated or printed so that one or both of

its surfaces will simulate the appearance of this kind of fur. Then when the pattern, such as that shown in Fig. 1, is cut in accordance with any desired pattern form and draped on the model, the effect on the eye of the artist is immensely improved so that without any difficulty he can at once perceive the propriety of the harmony and arrangement of the parts. This is especially 60 true if the garment to be made has more than one color in it. In other words, pattern material treated so as to have various appearances and different colors can be prepared in advance and parts of any desired 65 pattern cut therefrom. For instance, if the garment is to be made of fur and the body portion is to be made of one shade of brown fur and the collar portion of another shade of brown fur, the pattern for the collar can be 70 cut from the pattern material simulating the brown fur and the pattern for the body portion of the garment can be cut from pattern material formed in the other shade of brown. These when draped on the model will 75 substantially accurately simulate the appearance of the finished garment. The artist can then adjust the pattern until the proper fit is obtained and thereby know exactly what the finished garment is going to look like without cutting a single inch of the expensive 80 material.

In general, therefore, it will be perceived that I have provided a simple and highly efficient pattern and method of making the 85 same for assisting an artist to visualize and form a pattern or model of a garment of very expensive material without any waste whatsoever excepting that absolutely unavoidable in the cutting of the garment. By 90 this procedure I, therefore, not only save time, labor and material, but also make it possible for much more harmonious and finished products to be produced, because the artist is enabled to know in advance just 95 exactly what the finished garment is going to look like.

What I claim is:

1. As a new article of manufacture, a pattern piece for a garment of expensive material, the surface of the pattern piece prepared to simulate the finished material of which the ultimate garment is to be made.

2. As a new article of manufacture, a pattern, the parts of which are treated to simulate the material of which the ultimate garment is to be formed.

3. As an new article of manufacture, a pattern of a fur garment, the parts of the pattern being treated so that when draped on the model the surfaces of the parts of the pattern have the appearance of the material of which the corresponding parts of the finished garment are made.
4. The method of preparing garments of expensive material, which comprises treating a pattern material so that its surface simulates the appearance of the material of which the finished garment is to be made, cutting said material into a pattern, and then draping the pattern on the model or form whereby the appearance of the pattern on the form substantially exactly simulates the appearance and effect of the finished garment.

5. The method of preparing garments of expensive material which comprises treating a pattern material in any desired manner to simulate the effect on its surface of the material of which the garment is to be made and then cutting said material up into a pattern.

6. A pattern for a garment to be fashioned from expensive material such as fur or the like, consisting of a plurality of pattern pieces some or all of which are formed from a sheet of inexpensive material having a surface thereof prepared to simulate the appearance of the expensive material whereby when the pattern pieces are assembled a replica of the finished garment to be made is produced.

ADOLF A. MEYER.
